*BOTTLE CAPPER

Harold G. Rice, Evanston, Ill., assignor, by mesne assignments, to Indestro Manufacturing Corp., Chicago, Ill., a corporation of Illinois

Application September 1, 1931; Serial No. 560,572

5 Claims. (Cl. 226—84)

My invention relates to bottle cappers and has as an object the provision of a device which is especially designed for applying to bottles caps of the well-known "Crown" type, said device being simple in construction, inexpensive to fabricate, rugged and generally efficient.

A further object of my invention is to provide in a bottle capper having a rotary shaft with an operating handle or crank secured thereto, stop means for retaining the handle and capping member in elevated position whereby the machine may be operated rapidly and conveniently in the capping of a large number of bottles.

15 Various other objects and advantages will become apparent as the description proceeds.

Referring now to the drawings forming a part of this specification and illustrating a preferred embodiment of my invention,

20 Figure 1 is a perspective view of an improved bottle capper embodying my invention with a bottle in capping position thereon.

Figure 2 is an enlarged fragmentary elevational detail of a portion of the same.

25 Fig. 3 is an elevational view from a plane at right angles to that of Fig. 2 and from the right thereof.

Fig. 4 is a sectional view taken substantially on the line 4—4 of Fig. 2.

30 Fig. 5 is a plan view of the operating shaft of the device.

I have shown my invention as applied to a type of bottle capper such as that disclosed and claimed in my Patent No. 1,805,295, granted May 35 12, 1931. However, my invention is applicable to various other types of bottle cappers and is not limited to the specific type shown herein.

Referring to the drawing, the numeral 10 represents a base portion, the corners of which may 40 be perforated as at 11, for nails, screws or the like, whereby the device may be secured to a table or other support. Rising from the base, and in my preferred embodiment integral therewith, is a pedestal 13 which, as shown clearly in

45 Fig. 1, rises substantially vertically from the base 10 and then adjacent its upper portion extends forwardly as at 14. The pedestal 13 in my preferred embodiment is substantially of a 50 T-shaped section but obviously may be of other desired and convenient forms.

On the upper extremity of the pedestal 13 is formed, preferably integrally therewith, a substantially horizontal sleeve 16 and also a substantially vertical sleeve 18. The sleeve 18 is

formed forwardly of the sleeve 16 and communicates therewith. The sleeve 16 is apertured as at 20, which aperture may be adjacent the upper portion of the sleeve as shown, the peripheral edge of the sleeve being indented as at 21 opposite the aperture 20.

Slidably mounted in the sleeve 18 is a plunger 22 carrying adjacent its lower extremity a capping head 23. The plunger has formed on one side thereof, a plurality of teeth 24 constituting a rack, and adjacent the upper and lower extremities of the rack shoulders 25 extend beyond the outer edges of the teeth 24 so as to provide stops for limiting the vertical displacement of the plunger.

Rotatably and slidably mounted in the sleeve 16 is a shaft 27 having secured thereto a radially extending operating handle or crank 28. Formed on the shaft 27 is a plurality of teeth 30 constituting a pinion cooperating with the rack 24. Adjacent the pinion teeth 30 the shaft 27 is of reduced diameter as shown at 31, the outer extremity of this reduced portion being threaded to engage a nut 32 or the like. A helical compression spring 33 is coiled around the reduced portion 31 of the shaft between the nut 32 and the peripheral face of the sleeve 16 so as to normally urge the shaft 27 toward the left (Fig. 2) and the pinion teeth 30 into engagement with the rack teeth 24.

The shaft 27 is provided with a radially extending cavity 35. This cavity is so placed as to be substantially in line with the aperture 20 of the sleeve 16 when the device is in operative position, and the aperture 20 and cavity 35 are so arranged as to be in registry with each other when the handle 28 is in elevated position. Seated in the cavity 35 is a helical compression spring 36 and a ball 37, the spring 36 resiliently urging the ball outwardly of the shaft. As clearly shown at 38 in Fig. 4, the spring and ball may be retained in the cavity 35 after they have been inserted therein by spreading the metal of the shaft on opposite sides and adjacent the outer edge of the cavity. This may be accomplished by striking the shaft 27 adjacent the opening of the cavity 35 with a blunt instrument, or in any other suitable manner.

The operation of the device is thought to be obvious from the above description. The pinion 30 of the shaft 27 is normally in engagement with the rack teeth 24 of the plunger 22, so that the plunger may be reciprocated by means of the handle 28. As shown in Figs. 1 and 2 (dotted in Fig. 2) the device may be adjusted for bottles of

different sizes by shifting the shaft 27 to the right (Fig. 2) against the resilient action of the spring 33 so as to disengage the pinion from the rack, whereupon the plunger 22 may be axially displaced upwardly or downwardly. After the plunger has been so adjusted the shaft 27 is released and is moved back to normal position by the spring 33.

After a capping operation, most conveniently 10 accomplished by rotating the handle 28 downwardly, the handle is returned to elevated position substantially as shown in Fig. 3, so that the ball 37, urged by the spring 36, slips into the cavity 20 of the sleeve 16, when it comes into registry with the cavity, as shown best in Fig. 4. In this way the handle 28 is retained in elevated position while the capped bottle is removed from base 10 and an uncapped bottle is brought into capping position. Hence both hands of the operator are left free to manipulate the bottles between the successive capping operations. Otherwise, in the absence of such retaining means, the handle would be likely to drop by gravity and the plunger and capping member would be in a position to impede the placing of a new bottle on the base. Hence, it will be seen that, by means of my improvement, a great deal of time may be saved when a large number of bottles are to be capped and much inconvenience and annoyance 30 may be avoided and a large number of bottles may be capped most expeditiously.

Various modifications, variations and improvements coming within the spirit of my invention will doubtless occur to those skilled in the art 35 and hence I do not wish to be limited to the specific form disclosed herein or uses mentioned except to the extent indicated in the appended claims, which are to be interpreted as broadly as the state of the art will permit.

40 I claim as my invention:

1. In a device of the class described, the combination of a support, a bearing carried thereby, a capping member reciprocally carried by said support and having rack teeth formed thereon, a shaft rotatably mounted in said bearing and having a pinion formed thereon, said pinion being normally in cooperative relation with said rack, a handle carried by said pinion, and means for locking said pinion and capping member in elevated position, said means comprising a resilient member interengaging between said shaft and said bearing and rendered effective or ineffective by movement of said shaft.

2. In a device of the class described, the combination of a support having a horizontal bearing portion, said bearing portion having a depression on the inner wall thereof, a capping member reciprocally carried by said support, a shaft rotatably mounted in said bearing, said shaft having a substantially radial cavity formed therein, and means for locking said shaft in a predetermined axial position relative to said bearing comprising a resilient member and an interlocking member seated within the cavity of said shaft, said interlocking member being urged outwardly by said resilient member, whereby it may engage

in the cavity of said bearing when moved into registry therewith.

3. In a device of the class described, the combination of a support having a horizontal bearing portion, said bearing portion having a depression on the inner wall thereof, a capping member reciprocally carried by said support, a shaft rotatably mounted in said bearing, said shaft having a substantially radial cavity formed therein, and means for locking said shaft in a predetermined axial position relative to said bearing comprising a resilient member and a ball seated within the cavity of said shaft, said ball being urged outwardly by said resilient member, whereby it may engage in the cavity of said bearing when moved 15 into registry therewith.

4. In a device of the class described, the combination of a frame comprising a base portion and a vertical, overhanging guide portion and having a pair of spaced axial horizontal bearing 20 apertures of different diameters adjacent said guide portion, a capping member vertically slideable in said guide portion and having rack teeth formed thereon, a shaft having trunnions of different diameters rotatably journaled in and extending outward of said bearings and having a pinion thereon of external diameter not greater than the diameter of the larger of said apertures and having an endwise displacement within said bearing sufficient to disengage said pinion from 30 the rack teeth of said plunger, a compression spring disposed on said smaller trunnion extension and serving to maintain said pinion at operative engagement with the rack while permitting a sufficient sliding movement of the pinion to 35 unmash the same from the rack so as to permit free sliding movement of the capping member, and means for locking said shaft relative to said guide portion whereby said capping member may be retained in elevated position.

5. In a device of the class described, the combination of a frame comprising a base portion and a vertical, overhanging guide portion and having a pair of spaced axial horizontal bearing apertures of different diameters adjacent 45 said guide portion, a capping member vertically slideable in said guide portion and having rack teeth formed thereon, a shaft having trunnions of different diameters rotatably journaled in and extending outward of said bearings and having a pinion thereon of external diameter not greater than the diameter of the larger of said apertures and having an endwise displacement within said bearing sufficient to disengage said pinion from 50 the rack teeth of said plunger, a compression spring disposed on said smaller trunnion extension and serving to maintain said pinion at operative engagement with the rack while permitting a sufficient sliding movement of the pinion to unmash the same from the rack so as to permit free 55 sliding movement of the capping member, and means for locking said shaft relative to said guide portion whereby said capping member may be retained in elevated position, said locking means being rendered operative or inoperative 60 by displacement of said shaft.

HAROLD G. RICE.
